UNITED STATES PATENT OFFICE

PHILIP MARQUAND, OF NEWBURYPORT, MASSACHUSETTS, ASSIGNOR TO EDGE MOOR IRON COMPANY, OF EDGE MOOR, DELAWARE, A CORPORATION OF DELAWARE

BOILER CONSTRUCTION

Application filed July 9, 1928. Serial No. 291,461.

My invention relates to water tube boilers and has particularly for its object to provide for such close spacing of the water tubes as will insure a high speed of furnace gas travel in contact with the water tubes and at the same time provide for ample ligaments between the tube holes in the drums with which the water tubes are connected and with this object in view a leading feature of my invention consists in combining with upper and lower drums formed with tube holes spaced, and preferably symmetrically spaced, to provide ample ligaments between them, a series of connecting water tubes so bent that while their upper and lower ends will fit in the tube holes of the drums, a greater part of their length extending through the gas pass of the boiler setting will be disposed in much closer proximity to each other than they are at the points where they connect with the tube holes in the drums, thus forming restricted passages between them through which the furnace gases will move with high velocity.

Other features of my invention will be best understood as described in connection with the drawings in which I have illustrated two constructions, both embodying my invention in different modifications.

In the drawings,

Figure 1 is a side elevation of a boiler made up of elements embodying my invention.

Figure 2 is a cross section on the line 2—2 of Fig. 1.

Figure 3, a plan view of a portion of a tube plate used in the construction of the drums of my boiler elements in this case. The plate is one used in the construction of the rear upper drum of the boiler structure shown in Fig. 1.

Figure 4 is a view similar in general character to Fig. 1, but showing the modified construction embodying my invention.

Figure 5 is a cross sectional view on the line 5—5 of Fig. 4, and

Figure 6 is a plan view of the structure shown in Fig. 4, partly broken away to show the details of construction.

As shown in both modifications, I have illustrated my improvements as applied to a single pass water tube boiler, A indicating the furnace chamber, A¹ a horizontal pass for the furnace gases in which the boiler elements are located and A² the outlet pass for gases. Referring first to the construction shown in Figs. 1, 2, and 3, B is a front boiler element, C a rear boiler element and D a superheater located in the horizontal pass between the two elements. The front boiler element is made up of upper and lower drums, as indicated at E and E¹, provided with symmetrically disposed tube holes on their opposite faces, said tube holes being so spaced as to leave ample ligaments between them as indicated, for instance, in Fig. 3. The tube holes are indicated at e, e, etc. and at e¹, e¹, etc. The tubes connecting the upper and lower drums are bent tubes, so curved that their upper and lower ends will register with and fit into the symmetrically disposed tube holes in the drums while the greater part of their length extending through the gas pass will lie in much closer proximity to each other than is the case with the tube holes into which they fit. As shown, the tubes F, F, F, are disposed in a group which, as shown in Figs. 1 and 2, leave narrow gas passages between them, thus insuring a high speed of flow of the gases contacting with this group of tubes; the tubes F¹ and F² lying in front of the group of tubes F are, as shown, more widely spaced from the group and from each other so that they will be exposed to the radiant heat of the furnace. In this modification a second group of tubes, indicated at G, G, G, are similarly disposed with regard to the drums and each other and to the group of tubes F, F, F, forming again a series of narrow gas passes for the furnace gases coming in contact with them.

A second boiler element in my illustrated construction consists of the headers H and H¹, also provided at their opposite faces with symmetrically disposed tube holes with ample ligaments between them and connected by groups of bent tubes indicated at I

and J which, for the greater part of their length will lie close together so as to form, as in the case of the first element, narrow gas passes, insuring a high speed of flow for the furnace gases contacting with these two groups. The rear boiler element in this construction is connected with the front element by tubes indicated at K connecting the outer ends of the drum H with the outer ends of the drum E¹ and lying preferably outside the gas pass which in boilers of this type is best made of contracting area so as to maintain a comparatively high speed of transmission of the gases which, of course, are contracting in bulk as they are cooled down by contact with the water tubes. The upper drums E and H are shown as connected by pipes L lying at or below the water level in the drums and pipes M connecting with the steam space of the drums.

I have shown as a means for delivering feed water to the lower drum a header N extending across the top of the flue and connected to the lower drum by a series of water tubes N¹ extending across the flue and connecting with the drum H¹. This construction is not my invention but was invented by William B. Bradford, of Wilmington, Delaware.

30. The modification illustrated in Figures 4, 5, and 6, does not differ except in details of arrangement of the water tubes from the construction illustrated in Figures 1, 2, and 3. The tube banks in the modification of Figures 4, 5, and 6, in the ends of the front section are curved so as to form a series of banks each made up of two rows of tubes as indicated at f, g, g¹; as in the case of the first described modification, I do not so curve the two front rows of tubes as to make them close together but leave them spaced, as indicated at f¹, f², so that they will receive the full radiant heat of the furnace.

45. In the rear section of the boiler, the water tubes are so disposed as to form six closely spaced tube banks as indicated at i, i¹ and i², j, j¹ and j².

50. O and O' indicate baffles which it is advisable to use in connection with the boiler elements. P, Fig. 1, indicates the steam connection from the drum H to the superheater indicated at D. Q, Q, Fig. 4, indicate dampers for controlling the flow of gases through the horizontal pass of the construction illustrated.

55. The operation of my improved boiler construction will be clear from what I have already said. The bending of the water tubes so that they will at the same time register with the comparatively widely spaced tube holes in the drums and through the greater part of their length lie much closer together than is the case with the tube holes in the drums obviously insures the desired high speed of transmission of

the gases contacting with the tubes and this is the first object of my invention.

Having now described my invention, what I claim as new and desire to secure by Letters Patent, is:

1. A water tube boiler element adapted for use with a one direction transverse flow of fire gases through its tube banks comprising in combination two drums provided with tube holes spaced to leave substantial ligaments of sheet metal between them and one or more banks of tubes the intermediate and greater part of the length of which are in each bank disposed parallel to each other in spaced relation which leaves between them narrow gas passes substantially narrower than the spaces between the tube holes, said tubes having their ends spread apart and secured in the tube holes of the drums all of the tubes in each boiler element 75 in the rear of the tube rows between which contracted gas passages are first formed being disposed as described to form contracted gas passages throughout the entire depth 80 of the tube banks.

2. A water tube boiler element adapted for use with a one direction transverse flow of fire gases through its tube banks comprising in combination two drums provided on their opposite faces with symmetrically disposed and evenly spaced tube holes spaced to leave substantial ligaments of sheet metal between them and a plurality of banks of tubes the intermediate and greater part of the length of which are in each bank disposed parallel to each other in spaced relation which leaves between them narrow gas passes substantially narrower than the spaces between the tube holes, said tubes having their ends spread apart and secured 100 in the tube holes of the drums all of the tubes in each boiler element in the rear of the tube rows between which contracted gas passages are first formed being disposed as described to form contracted gas passages 105 throughout the entire depth of the tube banks.

3. A boiler element having the features of claim 1 and having disposed in front of the front bank of tubes one or more rows of 115 tubes spaced from said bank and from each other by approximately the distance between the tube holes in the drums.

4. A boiler element having the features of claim 1, in which the closely spaced portions of the tubes are straight and uncurved.

PHILIP MARQUAND.
